RECTIFIER

George H. Shoemaker, Brooklyn, N. Y., assignor
to Federal Telephone and Radio Corporation,
a corporation of Delaware

Application April 7, 1942, Serial No. 438,001

1 Claim. (Cl. 175—366)

This invention relates to new and useful improvements in rectifiers and more particularly to selenium rectifiers.

Heretofore, selenium rectifiers were made by depositing a layer of selenium on a metal plate and then applying a continuous conducting coating to the exposed surface of the selenium with one or more metals or a suitable alloy.

In accordance with the present invention the conducting coating of the exposed surface of a selenium rectifier is divided into a plurality of distinct and electrically independent areas. A single rectifier disc so constructed may be connected into circuit as two rectifiers, e. g., in a center tapped rectifier connection or by connecting the separate areas in parallel. Each division of the rectifier may be used independently of the other.

The drawing illustrates in Fig. 1 a top plan view and in Fig. 2 a vertical cross-section of an embodiment of the invention.

1 is a selenium disc having a central perforation 2. The selenium is deposited on a metal

plate 5. A suitable mask protecting the edge and a transverse stripe is applied to the exposed selenium surface and a metal alloy is sprayed thereon. A metallic coating will form on the selenium in two mechanically and electrically distinct areas 3 and 4 laterally spaced from one another by a transverse stripe of selenium. The rectifier disc is then electrically formed, contact being made with both areas 3 and 4.

After the customary testing and grading each half 3, 4 may be considered as an individual disc in connecting the rectifier in circuit.

What is claimed is:

In a rectifier disc, a flat metal plate, a selenium layer thereon, and a conducting coating 15 on the selenium layer, said disc having a central perforation extending through said plate, layer and coating, the coating being divided into a plurality of substantially equal areas covering the entire exposed selenium surface except a narrow stripe extending radially from the perforation between said areas and along the edge.

GEORGE H. SHOEMAKER.
